PAINT ROLLER FRAME

Gene M. Wiegand, Conneaut, Ohio, assignor to The Wooster Brush Company, Wooster, Ohio, a corporation of Ohio

Filed May 24, 1961, Ser. No. 112,419

3 Claims. (Cl. 29—116)

This invention relates to devices for applying paint or other liquid coating material to a surface for the purposes of protection, decoration, and the like; and more particularly it relates to a rotary type paint applicator commonly referred to as a paint roller.

Paint rollers conventionally comprise a rotatable frame upon which is removably and telescopically mounted a cylindrical member comprising a rigid, tubular core having an outer peripheral covering of absorbent material. The covering is first saturated with the liquid coating material to be applied, and subsequently by rolling said cylindrical member across a surface to be painted, said material is transferred in a thin, even layer upon the surface.

The present invention is directed to an improved paint roller frame adapted to receive and frictionally hold a cylindrical paint applying member as above described and has for a general object the provisions of a bird cage type frame of improved construction.

A more specific object of this invention is to provide a frame of the above type which is diametrically, resiliently compressible whereby it exerts a radially outwardly directed reactive force against a tubular applying member telescoped thereover.

Still another object of this invention is to provide such a frame having longitudinally displaceable end bearing members which automatically adjust themselves in response to a compressive force exerted diametrically inwardly upon the central portion of said frame.

A further object is to provide a frame having the above characteristics which is provided with a plurality of removable, resilient longitudinal connecting members which greatly facilitate the manufacture and assembly of the frame.

Yet another object of this invention is to provide such a paint roller frame which has improved connection means for mounting the resilient connecting members to the end bearing members.

Other objects of this invention and the invention itself will be readily understood from the following description and the accompanying drawings, in which said drawings:

FIG. 1 is a plan view of the paint roller frame and associated parts;

FIG. 2 is a transverse section taken along the line 2—2 of FIG. 1;

FIG. 3 is a section taken along the line 3—3 of FIG. 2; and

FIG. 4 is an inner end elevation of one of the end bearing members alone.

Referring now to the drawings in all of which like parts are designated by like reference numerals, at 10 there is generally shown a roller frame rotatably mounted upon a spindle 11. The spindle 11 is integrally connected with a parallel, axially laterally spaced support member 12 by means of a straight, perpendicular connected portion 13. As best seen in FIG. 1, the spindle 11, the support 12, and the connector portion 13 form a generally U-shaped element manufactured from a single length of preferably metal rod material wherein the spindle 11 is approximately twice the length of the support portion 12. The end of the support portion 12 opposite the connector portion 13 is provided with a right angularly bent handle

2

portion 14 which is axially parallel with the connector portion 13 and is directed away from the spindle 11. The handle portion 14 is provided with an enlarged gripping portion 15 whereby the paint roller is manually grasped during the painting operation.

The spindle 11 is swaged adjacent its proximal end to provide radially outwardly projecting stop members 16 against which one end of the roller frame 10 abuts. The stop members 16 prevent the roller frame 10 from moving laterally into frictional contact with the connector portion 13 and thereby assure that said roller frame will rotate freely upon the spindle 11.

The roller frame 10 comprises a pair of end caps or bearings 20 rotatably mounted upon the spindle 11 in longitudinally spaced relation to each other, connected to each other by means of a plurality of bowed rods 21, and preferably formed of molded nylon. As best shown in FIGS. 1 and 3, each rod 21 is bowed radially outwardly with respect to the spindle 11 throughout the generally medial portion of said rod. As best seen in FIG. 3, the ends of each rod 21 are provided with right angularly bent, radially inwardly directed hooks 22. It will be understood that the hook 22 as illustrated in FIG. 3 is identical with a similar hook disposed at the opposite end of each rod 21. There are preferably four of said rods which are circumferentially evenly spaced around the roller frame 10 with the bowed medial portion of each rod projecting radially outwardly from the axis of said roller frame.

Referring now to FIGS. 2—4, the bearings 20 are generally cup-shaped having flat bottom walls 23 and circumferential perpendicular flanges 24 at the periphery thereof. Each bearing 20 has a substantially deep recess 25 in the bottom wall 23 and an axially extending bearing collar 26 which is coaxially positioned and projects in the same direction as the flange 24. As well shown in FIGS. 2 and 4, each bearing 20 is provided with a plurality of preferably four sockets 27 adjacent the periphery of said bearing. Each socket 27 is in the form of a generally semi-circular depression in the flange 24, said depression extending throughout the length of the flange and terminating at the bottom wall 23. Adjacent said wall, each socket 27 is provided with an intersecting, radially disposed socket 28 which extends inwardly as far as a peripheral wall 25a of the recess 25.

Referring particularly to FIG. 4, it will also be noticed that each socket 27 is provided with a pair of oppositely facing, longitudinal protuberances 29 which tend to restrict and narrow the lateral opening of said socket adjacent the outer periphery of the bearing 20. It will also be noted that each bearing 20 is provided with radially disposed reinforcing webs 30 which extend from the bearing collar 26 outwardly to the walls of the socket 27. Additional reinforcing webs 31 are provided at circumferentially evenly spaced intervals between the webs 30 so that webs 30, 31 reinforce hub 26. Webs 31 are disposed between and connect the bearing collar 26 with the flange 24.

The pair of bearings 20 are positioned telescopically upon the spindle 11 with the flanges 24 and the bearing collars 26 directed toward each other. The rods 21 are forced or snapped into connection with the bearings 20 adjacent the ends of said rod. Each end of each rod is inserted with the hook 22 being directed into a radial socket 28 whereby said rod is forced laterally and radially into an associated socket 27 by a snap action. It will be understood that the protuberances 29 present some resistance to the entrance of the rod 21 into the socket 27 and that once said rod is seated within said socket, protuberances 29 prevent its radially outward displacement and hooks 22 in sockets 28 prevent turning of rod 21.

The roller frame 10 is retained upon the spindle 11 by

means of a hat shape cap 40 mounted upon the distal end of said spindle adjacent the outwardly disposed bearing 20. Said retaining cap is adapted to be telescoped over the distal end of the spindle 11 and is provided with a circumferentially continuous, radially outwardly projecting flange 41 which is positioned within the recess 25 of the outer bearing 20 and is slightly smaller in diameter than said recess. The retaining cap 40 is provided with preferably two inwardly struck prongs 42 which are directed generally toward the distal end of said spindle. It will be readily seen that when the retaining cap 40 is seated upon the spindle 11, the prongs 42 tend to penetrate slightly the outer peripheral surface of said spindle thereby preventing removal of said retaining cap.

When the roller frame 10 is fully assembled and rotatably mounted upon the spindle 11 with the retaining cap 40 in place, it will be noted that slight endwise movement of said roller frame is possible due to a slight axial displacement between the circumferential flange 41 of said retaining cap and the bottom of the recess 25 of the outer bearing 20. This amount of space, indicated at S in FIG. 3, allows for longitudinal expansion of the roller frame 10. When a paint applying member of conventional design is telescoped over the roller frame 10 (not herein illustrated), all of the bowed rods 21 are compressed slightly radially inwardly and hooks 22 move or rock in sockets 28 to thereby cause said roller frame to elongate with the resulting axial displacement of the bearings 20 in a direction away from each other. The space S is sufficient to allow this longitudinal expansion without causing the roller frame 10 to bind at either end, to highly stress bearings 20, or to in any way interfere with the free rotation thereof.

To use the paint roller device of this invention, a conventional paint applicator member having a rigid, tubular inner core and an outer absorbent peripheral covering is forcibly telescoped over the roller frame from the end thereof opposite the connector portion 13. The rods 21 are thereby squeezed inwardly and present to the inner peripheral surface of the rigid core sufficient outwardly expansive force to maintain the applicator member in position during use. The device is then grasped by the gripping portion 15, and covering of the applicator member is saturated with paint or similar material, after which it is rolled across the surface to be painted by means of the rotatable frame 10. Since there is only line contact between the rods 21 and the applicator member, no difficulty is encountered in removing the applicator member after use regardless of whether or not it has become clogged with paint on the inside. The construction of rods 21 hold the outer cover concentric with rods 21 and periphery of ends caps 20 and prevent circular movement between this cover and frame.

The device as herein illustrated and described is extremely rigid and durable in construction and the snap-in type rods and sockets greatly facilitates the assembly of the frame 10. The hooks 22 seated within the radial sockets 28 positively maintain the rods 21 against rotation whereby the bowing of each rod is always maintained in a radially outwardly projecting position to exert equal outward holding pressure on the cover. The reinforcing webs 30—31 give the bearing 20 great strength and rigidity whereas the cuplike design of said bearing cause them to be light in weight.

It will be understood that many departures from the details of this invention as herein disclosed and illustrated may be made without, however, departing from the spirit thereof or the scope of the appended claims.

What is claimed is:

1. A supporting frame for a paint-applying tubular structure, said supporting frame being rotatably mounted in use thereof and comprising a pair of spaced end heads and a plurality of circumferentially disposed resilient rod-like members extending between and carried by said end heads, said end heads being of a size to generally snugly

fit within said paint-applying tubular structure and said rod-like members having portions thereof which normally extend outwardly for resilient retaining engagement with said tubular structure, at least one of said end heads having a disc-shaped end wall, a generally cylindrical rim flange, and a centrally disposed hub having a spindle-receiving bore, said rod-like members having at one end thereof inwardly extending end portions for assembly with the rim flange and the end wall of said end head, said rim flange having circumferentially disposed and longitudinally extending grooves to receive said rod-like members adjacent their inwardly extending end portions and said end wall having inwardly extending grooves in alignment with said rim flange grooves to receive the inwardly extending end portions of said rod-like members, and said rim flange being provided with projections which restrict the width of the grooves therein and which projections are in spaced relation to the bottoms of said grooves, whereby in seating the rod-like members in said rim flange grooves, the rod-like members must be pushed past said projections, with the result that accidental escape of the rod-like members from said rim flange grooves is prevented.

2. A supporting frame for a paint-applying tubular structure, said supporting frame being rotatably mounted in use thereof and comprising a pair of spaced end heads and a plurality of circumferentially disposed resilient rod-like members extending between and carried by said end heads, said end heads being of a size to generally snugly fit within said paint-applying tubular structure and said rod-like members having portions thereof which normally extend outwardly for resilient retaining engagement with said tubular structure, at least one of said end heads having a disc-shaped end wall, a generally cylindrical rim flange, and a centrally disposed hub having a spindle-receiving bore, said rod-like members having at one end thereof inwardly extending end portions for assembly with the rim flange and the end wall of said end head, said rim flange having circumferentially disposed and longitudinally extending grooves to receive said rod-like members adjacent their inwardly extending end portions and said end wall having inwardly extending grooves in alignment with said rim flange grooves to receive the inwardly extending end portions of said rod-like members, the central portion of the end wall of said end head being recessed at the outer surface thereof to expose within said recess a portion of the spindle upon which the end head is rotatably mounted, and a hat shape retaining element telescoped over the end of said spindle for the retention of the end head thereon, at least a portion of said retaining element lying within said end head recess, said retaining element being provided with prong-like projections engageable with said spindle for end head retaining purposes.

3. A supporting frame for a paint applying tubular structure, said supporting frame being rotatably mounted in use thereof and comprising a pair of spaced end heads and a plurality of circumferentially disposed resilient rod-like members extending between and carried by said end heads, said end heads being of a size to generally snugly fit within said paint applying tubular structure and said rod-like members having portions thereof which normally extend outwardly for resilient retaining engagement with said tubular structure, at least one of said end heads having a disk shaped end wall, a generally cylindrical rim flange, and a centrally disposed hub having a spindle receiving bore, said rod-like members having at one end thereof inwardly extending end portions for assembly with the rim flange and the end wall of said end head, said rim flange having circumferentially disposed and longitudinally extending grooves to receive said rod-like members adjacent their inwardly extending end portions and said end wall having radially inwardly extending sockets in alignment with said grooves receiving the inwardly extending end portions of said rod-like members and retaining said members against

endwise movement relative to said end head, and said rim flange being provided with projections which restrict the width of the grooves therein and which projections are in spaced relation to the bottom of said grooves, whereby in seating the rod-like members in said rim flange grooves, the rod-like members must be pushed past said projections, with the result that accidental escape of the rod-like members from said rim flange grooves is prevented.
